[57] **CLAIM**

The ornamental design for a casting machine for dental prostheses, as shown and described.

DESCRIPTION

FIG. 1 is a front elevational view of a casting machine for dental prostheses showing our new design;

FIG. 2 is a rear elevational view thereof;

FIG. 3 is a top plan view thereof;

FIG. 4 is a bottom plan view thereof;

FIG. 5 is a side elevational view thereof;

FIG. 6 is an opposite side elevational view thereof;

FIG. 7 is a top, opposite side isometric view thereof; and,

FIG. 8 is a top, side isometric view thereof.

FIG.1**FIG.2****FIG. 3****FIG. 4****FIG. 5****FIG. 6****FIG. 7**

FIG. 8
